E. W. Marshall

UNITED STATES PATENT OFFICE.

HARVEY W. BELL, OF BOUND BROOK, NEW JERSEY, ASSIGNEE TO ARTHUR C. FRASER,
TRUSTEE, OF NEW YORK, N. Y.

STEAM POWER PLANT.

1,425,629.

Specification of Letters Patent. Patented Aug. 15, 1922.

Application filed April 26, 1917. Serial No. 164,649.

To all whom it may concern:

Be it known that I, HARVEY W. BELL, a citizen of the United States of America, and a resident of Boundbrook, county of Somerset, State of New Jersey, have invented certain new and useful Improvements in Steam Power Plants, of which the following is a specification, reference being had to the accompanying drawings, forming a part thereof.

My invention relates to new and useful improvements in steam power plants and its object is to provide a steam generator of extremely light and very simple construction which is capable of working at high efficiency. Another object is to provide a structure of such light weight that it is suitable for use with airplanes.

Another object is to combine a generator of my novel construction with a motor and a pump in such a way as to cause the water supply to the boiler to vary automatically with the speed of the motor.

These and other objects of my invention will be set forth hereinafter, and in order that my invention may be thoroughly understood I will now proceed to describe the same in the following specification, and will then point out the novel features thereof in appended claims.

Referring to the drawings:

Figure 1 is a longitudinal section of a boiler made according to and embodying my invention, together with a steam turbine, a condenser, a pump and other parts shown diagrammatically in elevation.

Figure 2 is a transverse section of the boiler, on a larger scale.

Figure 3 is a longitudinal section of a part of one of my improved boilers, also drawn on a larger scale than that used in Figure 1, in order to more clearly show its construction.

Like characters of reference designate corresponding parts in all the figures.

10 designates a helical pipe coil, of much greater length than diameter. It is preferably tapered somewhat so that its form is that of a long and comparatively narrow truncated cone. 11 is a water inlet pipe connected with one end of this pipe coil, and 12 is the steam outlet pipe connected with the other end of the pipe coil. The coil is covered with a heat insulator 13 such as

asbestos, outside of which is a metallic jacket 14.

At the steam outlet end of the structure a mouth piece 20 is provided which may be made flaring as shown. In the center of this mouth-piece is an oil burner 21 to which liquid fuel is supplied from a reservoir 22 through a pipe 23 in which is a valve 24. The reservoir 22 if below the burner is closed and arranged to be supplied with pressure introduced at 25.

The apparatus shown in Figure 1 is designed for use in an airplane. In this figure, 30 designates a steam turbine with which the steam pipe 12 is connected. 31 is the exhaust pipe from the turbine to a condenser 32 the vanes of which are curved and inclined as shown, and at the base of which is a water chamber 33. The water chamber is connected by a pipe 34 with the intake of a pump 35 which is driven by the turbine 30 and the outlet of which is connected with the water inlet pipe 11.

The turbine is preferably supplied with reduction gearing within the casing 36 by means of which its rotor is connected with a propeller shaft 37. The propeller 38 is preferably placed in front of the condenser 32 and the intake mouthpiece 20.

I will now describe the operation of this apparatus. A flame from the burner 21 is introduced at one end of the pipe coil 10 and the hot gases therefrom are passed through the tube formed by this coil. The heat is absorbed by the water in the pipe coil which is thereby turned into steam. The hottest end of the pipe coil is at the steam outlet end not only because the heat is introduced at this end but because of the circulation of water and steam in the coil. The result is that practically all of the heat is absorbed and that the gases discharged from the water inlet end of the coil are comparatively cool. Another result is that the water in the pipe coil enters at the condenser temperature and its temperature is gradually raised as it moves toward the steam outlet end. Before it reaches the outlet it is changed into steam and this steam as it advances becomes superheated. The tapered form of the pipe coil is preferred as it helps to make the absorption of the heat more complete.

The rotation of the turbine drives the

pump 35 which is arranged to supply water to the pipe coil as fast as it is needed. It is obvious that the circulation of water is proportional to the speed of the turbine. The speed of the turbine is proportional to the intensity of the flame and it follows that the speed of the turbine may be regulated by adjusting the valve 24. No other valve is needed, nor is it necessary to have any water gauge, injector or safety valve. The pipe coil 10 is made of material of sufficient strength to withstand high pressures and which will not burn out when filled with dry steam and subjected to the heat of the flame.

15 When the apparatus is used on an airplane the pipe coil tube is placed in a fore and aft position, so that the movement of the apparatus through the air will aid in carrying the gases through the long tube formed by the pipe coil. The flaring shape of the mouth-piece 20 assists this function as does also the relative position of the propeller 38 which acts as a fan. The gases thus introduced at one end of the tube formed by the pipe coil, pass freely therethrough but are retarded somewhat by the taper of the tube. The propeller also helps to keep the condenser 32 cool.

30 The apparatus is desirable for war airplanes as it has no delicate parts and is not easily vulnerable. It is immune from explosion and the fire risk is reduced to a minimum because the fuel oil used need not be of a volatile and highly inflammable character. 35 Steam may be generated instantly and the whole apparatus, especially the boiler itself, is extremely light in weight.

Of course this boiler is not limited to the use with airplanes which has been described 40 nor is it necessarily limited to the use of generating steam. It is well within the scope of this invention to use the novel structure as a heater for water for example, and I intend no limitations other than those imposed 45 by the appended claims.

What I claim is:

1. A steam power plant comprising a horizontally disposed boiler, a water inlet at the rear end, and a burner at the front end thereof, a motor, a connection between the boiler and the motor, a condenser, a connection between the motor and the condenser, a connection between the condenser and said water inlet and means for moving air 55 through the boiler.

2. A steam power plant comprising a horizontally disposed boiler, a water inlet at the rear end, and a burner at the front end thereof, a motor, a connection between the boiler and the motor, a condenser, a connection between the motor and the condenser, a connection between the condenser and said water inlet, a pump in said last named connection and means for moving air through 65 the boiler.

3. A steam power plant comprising a horizontally disposed boiler, a water inlet at the rear end, and a burner at the front end thereof, a motor, a connection between the boiler and the motor, a condenser, a connection between the motor and the condenser, a connection between the condenser and said water inlet, a pump in said last named connection, means for moving air through the boiler, and means for driving the pump at 75 variable rates.

4. A steam power plant comprising a horizontally disposed boiler, a burner at the front end thereof, a motor, a connection between the boiler and the motor, a pump arranged to force water into the boiler, a fan arranged to blow air through the boiler, and means for driving said pump and fan at 80 variable rates.

5. A steam power plant comprising a horizontally disposed boiler, a burner at the front end thereof, a motor having a shaft, a connection between the boiler and the motor, a pump having a driving connection with said motor shaft arranged to force water 90 into the boiler, and a fan also having a driving connection with said motor shaft arranged to blow air through the boiler.

6. A steam power plant comprising a horizontally disposed boiler, a water inlet at the rear end, and a burner at the front end thereof, a motor, a connection between the boiler and the motor, a condenser, a connection between the motor and the condenser, a connection between the condenser and said water inlet and means for moving air through the boiler, and manual means for adjusting the flow of fuel to the burner to thereby vary the rate of speed of said motor.

7. A steam power plant comprising a horizontally disposed boiler, a burner at the front end thereof, a motor, a connection between the boiler and the motor, a pump arranged to force water into the boiler, a fan arranged to blow air through the boiler, said 110 pump and fan being connected to be driven by the motor, and manual means for adjusting the flow of fuel to the burner to thereby vary the rate of speed of said motor, pump and fan.

8. A steam power plant comprising a horizontally disposed boiler, a water inlet at the rear end, and a burner at the front end thereof, a motor, a connection between the boiler and the motor, a condenser, a connection between the motor and the condenser, a connection between the condenser and said water inlet, and a fan in front of the condenser, said fan being connected to be driven by said motor.

9. A steam power plant comprising a horizontally disposed boiler, a water inlet at the rear end, and a burner at the front end thereof, a motor, a connection between the boiler and the motor, a condenser near 130

- the front end of the boiler, a connection between the motor and the condenser, a connection between the condenser and said water inlet, and a fan connected to be driven by the motor in front of the burner and the condenser.
10. A steam power plant comprising a horizontally disposed boiler, a water inlet at the rear end, and a burner at the front end thereof, a motor, a connection between the boiler and the motor, said motor having a shaft, a condenser near the front end of the boiler, a connection between the motor and the condenser, a connection between the condenser and said water inlet, and a fan on said motor shaft in front of the burner and the condenser.
11. A steam power plant comprising a horizontally disposed boiler, a water inlet at the rear end, and a burner at the front end thereof, a motor, a connection between the boiler and the motor, said motor having a shaft, a condenser near the front end of the boiler, a connection between the motor and the condenser, a connection between the condenser and said water inlet, a pump having a driving connection with said motor shaft in said last named connection, and a fan also having a driving connection with the shaft in front of the burner and the condenser.
12. A steam power plant comprising a horizontally disposed elongated, open-ended tube, a water inlet at the rear end, and a burner at the front end thereof, a steam outlet from the tube ahead of the water inlet, combined with a motor connected with said outlet, a condenser connected with the motor, a connection between the condenser and said water inlet, a pump in said last-named connection, connected to be driven by the motor and arranged to be driven thereby at variable rates, proportional to the steam delivered to the motor from said tube and means for moving air through the tube.
13. A steam power plant comprising a horizontally disposed elongated open-ended tube, a water inlet at the rear end and a burner at the front end thereof, a valve for controlling the burner, a steam outlet from the tube ahead of the water inlet, combined with a motor connected with said outlet, a condenser connected with the motor, a connection between the condenser and said water inlet, a pump in said last-named connection, connected to be driven by the motor and arranged to be driven thereby at variable rates, the speed of said motor and rate of delivery of said pump being dependent upon the adjustment of said burner valve, and means for moving air through the tube.
14. A steam power plant comprising a horizontally disposed elongated, open-ended tube, a water inlet at the rear end, and a burner at the front end thereof, a steam outlet from the tube ahead of the water inlet, combined with a motor connected with said outlet, an air-cooled condenser connected with the motor, a connection between the condenser and said water inlet, a pump in said last-named connection, and a fan in front of the tube and the condenser, said pump and fan being connected to be driven by the motor and arranged to be driven thereby at variable rates proportional to the steam delivered to the motor from the tube.
15. A steam power plant comprising a horizontally disposed elongated open-ended tube, a water inlet at the rear end and a burner at the front end thereof, a valve for controlling the burner, a steam outlet from the tube ahead of the water inlet, combined with a motor connected with said outlet, said motor having a shaft, a condenser connected with the motor, a connection between the condenser and said water inlet, and a pump in said last-named connection on the motor shaft and a fan also on the motor shaft in front of the tube and the condenser, the speed of the motor, pump and fan being dependent upon the adjustment of said burner valve.
16. A steam power plant comprising a horizontally disposed elongated open-ended tapered tube, a water inlet at the rear end and a burner at the front end thereof, a steam outlet from the front end of the tube, combined with a motor connected with said outlet, a condenser connected with the motor, a connection between the condenser and said water inlet, a pump in said last-named connection connected to be driven by the motor and arranged to be driven thereby at variable rates proportional to the steam delivered to the motor from the tube and means for moving air through the tube.
17. A steam power plant comprising a horizontally disposed elongated open-ended tapered tube, a water inlet at the rear end and a burner at the front end thereof, a valve for controlling the burner, a steam outlet from the front end of the tube, combined with a motor connected with said outlet, said motor having a shaft, a condenser connected with the motor, a connection between the condenser and said water inlet, a pump in said last-named connection connected to be driven by the motor and arranged to be driven thereby at variable rates proportional to the steam delivered to the motor from the tube and means for moving air through the tube.
18. A steam power plant comprising a horizontally disposed elongated open-ended tapered tube, a mouth piece at the front end thereof, a water inlet at the rear end and a burner in said mouth piece, a valve for controlling the burner, a steam outlet from the front end of the tube, combined with a motor connected with said outlet, said motor having a shaft, a condenser connected with the motor, a connection between the condenser and said water inlet, a pump in said last-named connection connected to be driven by the motor and arranged to be driven thereby at variable rates proportional to the steam delivered to the motor from the tube and means for moving air through the tube.

with a motor connected with said outlet, said motor having a shaft, an air-cooled condenser connected with the motor, a connection between the condenser and said water inlet, a pump having a driving connection with the motor shaft in said last named connection, and a fan also having a driving connection with the motor shaft and located in front of the mouth piece and the condenser, the speed of the motor, pump and fan being dependent upon the adjustment of said burner valve.

19. A movable steam power plant comprising an elongated open tube disposed in the direction of its movement, a flaring end at the front of said tube, an air outlet near the rear end and a burner at the flaring front end thereof, a steam outlet from the tube ahead of the water inlet, combined with a motor connected with said outlet, a condenser connected with the motor, a connection between the condenser and the water inlet, a pump in said last named connection and means for moving air through the tube.

25. 20. A power plant comprising a boiler having a tubular shell and a vaporizing pipe, a feed pump discharging into one end of said pipe, a motor receiving steam from the other end of said pipe, means controllable manually independently of the motor for introducing a forced flow of fluid fuel into the shell of said boiler, and means for forcing a flow of air therethrough, whereby the control of said fuel introducing means determines the rate of combustion and hence the rate of generation of steam in the boiler and development of power by said motor.

21. A power plant comprising a boiler consisting of an enclosing shell having opposite inlet and outlet openings, a coil of vaporizing pipe therein, a burner discharging subdivided fluid fuel under pressure into the inlet of the shell to heat said pipe, means for introducing air at said inlet, a feed pump forcing water into one end of said pipe, a steam pipe leading from the opposite end of said pipe, a motor receiving steam from such steam pipe without manual control of the flow of steam to the motor, manually-controlled means for varying the flow of fuel to said burner, whereby to control the rate of combustion and of generation of steam, and means for varying the feed from said pump proportionally to the volume of steam fed to the motor.

22. A power plant comprising a boiler, a feed pump supplying water thereto, a motor driven by steam from said boiler, means for heating said boiler comprising a burner fed with fluid fuel under pressure, means for varying manually the supply of fuel thereto, and means for varying the delivery of feed water to the boiler proportionally to the outflow of steam to the motor, whereby the rate of power develop-

ment is controlled by varying the introduction of fuel to said burner to vary the rate of combustion and hence the volume of steam delivered to said motor.

23. A power plant comprising a boiler, having a tubular shell and a vaporizing coil therein, a feed pump forcing water into the inlet of the coil, a motor receiving steam from the outlet end of the coil, the discharge from the boiler to the motor being free from manual control, a burner at the inlet end of the boiler, means for forcing liquid fuel to said burner, means for introducing a flow of air at the burner, and means for varying at will the rate of combustion by which the boiler is heated, whereby the rate of development of power is controlled by such combustion-varying means.

24. A power plant comprising a boiler having a tubular shell and a vaporizing pipe, a feed pump discharging into one end of said pipe, a motor receiving steam from the other end of said pipe, the discharge from the boiler to the motor being free from manual control, and means for varying at will the rate of combustion by which the boiler is heated, whereby the rate of development of power is controlled by such combustion-varying means.

25. A power plant comprising a boiler having a tubular shell and a coil of vaporizing pipe therein, a feed pump forcing water into one end of said pipe, a pipe leading steam from the other end of said pipe, a burner introducing fluid fuel into the boiler at said latter end, means for forcing air into said latter end, whereby the greatest heat is generated toward the delivery end of the boiler so that the generated steam may be superheated, the discharge from the boiler to the motor being free from manual control, and means for varying at will the rate of introduction of fuel, whereby the development of power is controlled by such latter means.

26. A power plant comprising a boiler having a tubular shell and a coil of vaporizing pipe therein, a feed pump forcing water into one end of said pipe, a pipe leading steam from the other end of said pipe, a burner introducing fluid fuel into the boiler at said latter end, means for forcing air into said latter end, whereby the greatest heat is generated toward the delivery end of the boiler so that the generated steam may be superheated, the discharge from the boiler to the motor being free from manual control, and means for varying at will the rate of introduction of fuel, the said pump and air forcing means connected to the motor to be driven at varying rates proportional to varying rates of power generation.

27. A power plant comprising a boiler having a tubular shell and a coil of vaporizing pipe therein, the shell tapering from

one end to the other, a feed pump forcing water into said pipe at the smaller end of the shell, a discharge pipe leading steam from said pipe at the larger end of the shell, a burner introducing fluid fuel into the boiler at said latter end, means for forcing air into said latter end, whereby the hot gases flowing through the boiler pass into a smaller

area as they cool, and means for varying at will the rate of introduction of fuel, whereby the development of power is controlled by such latter means.

In witness whereof, I have hereunto set my hand this 24 day of April, 1917.

HARVEY W. BELL.
